UNITED STATES PATENT OFFICE.

EBEN RAY PACKER, OF NEW ROCHELLE, NEW YORK, ASSIGNOR TO Q. & C. COMPANY, OF NEW YORK, N. Y., A CORPORATION OF MAINE.

EMERGENCY KNUCKLE FOR CAR COUPLERS.

Application filed February 16, 1920. Serial No. 358,999.

To all whom it may concern:

Be it known that I, EBEN RAY PACKER, a citizen of the United States, residing at New Rochelle, in the county of Westchester and 5 State of New York, have invented new and useful Improvements in Emergency Knuckles for Car Couplers, of which the following is a specification.

This invention relates to emergency knuckles for car couplings and consists of an improved construction and arrangement thereof of more fully to adapt it for universal use with the many standard types or makes of car couplings and which in addition possesses 10 important features and advantages over the types of knuckles as heretofore employed for emergency use.

My improved emergency knuckle is particularly designed for use with the many 15 standard types of railway car couplings which as is well understood are universally made in accordance with the M. C. B. standards but which vary considerably particularly in the shapes and contours of the draw heads and therefore impose strict constructional limitations which must be complied 20 with in the production of a practical emergency coupling. My improved knuckle is designed to conform to the standards and 25 moreover is of an improved construction which meets the many other and important conditions of this particular art. Important features thereof which contribute in successfully meeting the many requirements 30 include the following: It is peculiarly formed to be interchangeable with the standard knuckles of the many types of car couplings now on the market so as to be adapted for replacing the regular knuckles when 35 face worn or broken; it is adapted for effecting the locking of the parts where the usual locking parts are broken or defective; it is designed to be effective in coupling 40 where one of the pin lugs of the draw head is broken off; it is adapted for effecting the coupling with normal spacing so as not to increase the distance between the cars thereby avoiding danger of injury to trainmen 45 and permitting the proper connection of the air lines between cars; is constructed so as to insure the successful automatic operation in coupling the cars and may be conveniently and readily installed so as to avoid 50 delays to traffic.

A further important feature of my present invention consists in the provision of bearing or retaining means on the knuckle adapted to engage with the draw bar head so as to prevent excessive swinging or rotation of the knuckle in either direction without the employment of an elongated securing arm entering the opening in the draw bar proper as heretofore practised and the use of which is prohibited by the peculiar construction of certain recent types of couplings.

The described and other important features and advantages of my present invention are illustrated in the accompanying drawings wherein like reference numerals 70 are applied to the corresponding parts in the several views.

In the drawings:

Fig. 1 is a horizontal sectional view illustrating an approved embodiment of the present invention and illustrating the co-acting coupling member in dotted lines.

Fig. 2 is a vertical sectional view thereof showing my improved emergency knuckle 80 in elevation.

Fig. 3 is a horizontal sectional view corresponding to Fig. 1 illustrating a slightly modified form thereof, and

Fig. 4 is a vertical sectional view thereof corresponding to Fig. 2 and illustrating the desirable elongation of the coupling jaws.

As shown in the drawing my improved knuckle is illustrated as used to replace the ordinary knuckle of a standard type of railway car coupler. The body or supporting head 1 of the coupler as shown is of a standard modern type of draw bar head of hollow form, as illustrated, having its forward active surface of the usual contour conforming to the M. C. B. standards. As will be noted this type of coupler head is provided with the usual inclined jaw closing surface 2, superimposed pivot pin supporting lugs 3, 3 and is provided at its rear with a lateral wall or partition 4 of a form and size which would prohibit the use of an elongated holding arm of the jaw or knuckle 5 as heretofore customarily used. At 6 there is illustrated a housing or socket for the usual locking mechanism for the regular or ordinary coupling knuckle 7 as illustrated in dotted lines of Fig. 1.

The emergency knuckle 5 as here illus-

trated and in accordance with my invention is formed with the locking jaw 8 of a contour conforming to the M. C. B. standards and is provided with a vertical aperture 9 therethrough to receive the usual pivot pin 10 of the coupling whereby it is held in position. To retain the locking jaw 8 of the emergency knuckle in locking or coupling position, an external holding lug 12 is formed integrally thereon and adapted to engage the outer surface of the side wall 11 of the coupler head. The lug 12 is therefore operative to prevent swinging forwardly of the coupling jaw 8 and accordingly performs the function of the usual locking means in preventing releasing movement of the knuckle in the forward direction. It follows therefrom that in the event of the locking means of a coupler becoming broken the employment of this emergency knuckle will permit of obtaining an effective coupling with the jaw of ordinary type of a coacting coupling member. In automatic coupling under the described conditions it will be understood that the ordinary coupling knuckle 7 of the coacting coupler will be the swinging or movable member and will be deflected inwardly by the surface 2 into the locking position in the usual manner.

To successfully so operate and to be positive in its automatic coupling operation it is required that the emergency coupling jaw 8 shall also be secured from rotation or swinging inwardly toward or into its supporting head 2. For this purpose I have provided the emergency knuckle element with a rearwardly extending arm portion 14 having its outer surface 15 suitably positioned to engage with the inner surface of the side wall 13 of the coupler head thereby to act as a stop to prevent excessive movement inwardly of the jaw portion 8 whereby the latter cannot swing inwardly sufficient to prohibit the proper automatic coupling. The provision of both the external and internal engaging portions 12 and 14 of the knuckle will thus operate to secure the emergency knuckle in operative locked position at all times and the stops thus formed occupy but small space which permits of their being made with proper clearance to be interchangeable with the many types of coupler construction.

In Figs. 3 and 4 I have illustrated a desirable modified construction employing the described features of my improved knuckle but wherein the securing arm or lug 14 is somewhat elongated to extend within the coupler head whereby its inner extremity 16 will be adapted for engagement with the inner surface of the side wall 17 of the coupler head to supplement the stop 12 in preventing unlocking movement of the jaw 8. The provision of this arm 14 and par-

ticularly in its elongated form as shown in this modification is desirable in rendering the emergency knuckle effective under the conditions of a broken off pin lug 3 in that the arm 14 by engagement with the upper or lower wall of the coupler head will operate to maintain the pivot pin 10 in its vertical position and prevent angular stress on the remaining pin lug 3.

A further important feature of the modified form of Figs. 3 and 4 consists in the vertical elongation of the working face of the coupling hook or jaw 8 as indicated. In the ordinary emergency knuckle the working face of the jaw members are not over about 8" in height and in accordance with this modification I have extended the jaw member 8 vertically in both directions so as to give it a height equal to two or preferably three times the height of the ordinary knuckle. In this way it is impossible for an engaging knuckle to slip above the top or below the bottom of the emergency knuckle, no matter how uneven the track may be and therefore all danger of accidental uncoupling because of an uneven track is obviated.

A knuckle having a vertical height or depth of twenty-four inches, as ordinarily made, would be too heavy to be conveniently handled and therefore, in order to make the device sufficiently light, I make the member 8 hollow, preferably by coring out deep recesses 18 extending downwardly from the top face and upwardly from the bottom face. Cored out in the manner described, lightness is secured without detracting from the strength of the knuckle.

While I have described desirable embodiments of the features of my invention it will be understood that modifications may be made therein without departing from the scope of the invention as defined in the appended claims.

I claim—

1. An emergency knuckle adapted to take the place of the ordinary knuckle in a car coupling comprising a body provided with an aperture for receiving the pivot pin of the coupling for holding it in place, a coupling jaw and retaining means for retaining said jaw in locked position, said retaining means comprising external and internal shoulders positioned to engage the side wall of the coupler or draw bar head, said internal shoulder being formed by a comparatively short arm adapted by vertical engagement with the interior of the coupling head to retain the emergency knuckle in position and effective for locking when a pin lug of the coupler head is broken off and said arm being formed whereby its inner extremity is positioned to engage at opposite sides with an internal wall of the coupler head when rotated in either direction.

and of such length as to be contained wholly within the forward opening of the coupler head.

2. An emergency knuckle adapted to take the place of an ordinary knuckle in a car coupling comprising a body provided with an aperture for receiving the pivot pin of the coupling for holding it in place, a coupling jaw and retaining means for retaining said jaw in locking position, said retaining means comprising external and internal shoulders positioned to engage the side wall of the coupler or draw bar head and said internal shoulder being formed as a rear-

wardly extending arm of a form and length 15 adapted to engage the inner wall of the forward opening of the coupler head at the opposite side from the pin to resist forward pull on the jaw and said internal shoulder or arm being of such length as to 20 avoid the necessity of removing of the usual locking parts as to be contained wholly within the forward opening of the coupler head.

In testimony whereof I have signed my 25 name to this specification.

EBEN RAY PACKER.
